UNITED STATES PATENT OFFICE.

WILLIAM L. HANCOCK, OF DALLAS, TEXAS, ASSIGNOR TO THE MURRAY COMPANY, OF DALLAS, TEXAS, A CORPORATION OF TEXAS.

PRESS-DOOR LOCK AND RELEASE.

Application filed April 25, 1925. Serial No. 25,958.

My invention is an improved cotton press door fastener and release, designed to permit the doors, after the bale has been compressed, to be gradually released and opened.

5 In the drawings:

Figure 1 shows an alternative construction for the operating handle;

Figures 2 and 3 are a plan and side elevation, respectively of a press box, in closed 10 position, fitted with my improvement;

Figure 4 is a side elevation of a press box fitted with my improvement, the doors in released position;

Figure 5 is a side elevation of the eccentric 15 cam;

Figure 6 is a view of Figure 5 from the right hand side;

Figure 7 is a detail of the link member;

20 Figure 8 is a detail of the actuating shaft; Figure 9 is an end view of Figure 8;

Figures 10 and 11 are sketch views of the actuating cam in locking and releasing position respectively;

25 It will be obvious of course that my improvement is applicable to a press of any size, single or double and without regard to whether the pressure is applied from below or above or by a screw, hydraulic ram, or other means, since my improvement relates 30 only to means for securing and releasing the doors of the press box.

In cotton compressing installations, the press is mounted upon substantial foundation sills, which also carry means for operating the press follower or moving platen, either up or down. The upper platen may be removed to fill the press box with cotton, if the installation is a single press compress and when the press box is filled with 40 cotton, the upper platen is returned to position and the doors of the press box are closed and locked in closed position by hooks or other locking means. The follower or lower platen is then actuated upward to 45 compress the cotton into the upper part of the press box, against the upper platen. When the compression is complete the doors of the press box are released and lowered and the bale tied and removed.

50 In order to release the door it is necessary to remove or release the locking means and it is an object of my invention to provide a securing mechanism, which may be operated to release the doors gradually and 55 permit the cotton to expand laterally, but

gradually and without sound or shock and which shall permit the locking links to slide off the cams sidewise when the release is effected.

This I accomplish as follows: referring 60 to the drawings, illustrating an embodiment of my invention, at the upper corners of the front doors 6, I mount, preferably upon cross member 71, castings 62 carrying each a bearing for a shaft 63 which passes across 65 the front of the door 6 through the bearings in castings 62, the ends of the shaft 63 projecting outside of the bearings at each end. The projecting ends of the shaft 63 are squared, as at 63^a and the extreme end, 63^b 70 are bevelled off (see Figures 8 and 9).

Upon the upper corners of the rear door 6^a are mounted preferably upon a cross-member 71, castings 64, in which are loosely secured the ends of jointed links 9 (see Figures 7 75 and 4) the loop 91 being the free end. The shaft 63 is mounted in the bearings of castings 62, the squared and bevelled ends projecting outside the castings 62. Upon each of the squared ends of the shaft are mounted 80 respectively a mutilated eccentric cam, 10 having a hug 11 through which a square aperture corresponding with the squared ends of the shaft 63. This eccentric cam is of usual form at the positive section 12, that 85 is, the part of greatest radius from the shaft 63 and with preferably a slight groove to better retain the loop or strap 91. At the opposite section, the cam is mutilated, being bevelled off at 13 in a slant which corresponds with the beveled end 63^b of the shaft 63 (see Figure 6), and also the strap or loop seat of the cam, is beveled from the hub side to the outside of the cam, as indicated at 13^a, Figure 6, so that when the cam is turned to 90 released position, the strap or loop may slide off the cam sidewise, without any obstruction. The cam, as shown in Figures 5 and 6 is in a position midway between locking and released position. These cams are secured against 95 any movement longitudinally of shaft 63, by a set-screw 14.

With a hub 11 of one cam 10 is preferably combined a handle, 20, by which the hub, the shaft 63 and the other cam at the other 105 end of the shaft may be actuated. If desired, however, the handle may be separately mounted at one end of the shaft, within the cam, to turn the shaft and its associated cams (see Figure 1) the cam being at the extreme 110

- end of the shaft. The handle 20 will in any event be so organized with the shaft and cam that when the cam is in released position, as in Figure 4, the handle will extend 5 vertically upward, and when the cam is in locking position, as in Figure 3, will extend vertically downward, in which position it may be secured by a catch, 21. The use of the handle shown in Figure 12 is obvious.
- 10 The square aperture in the end of the handle is placed on the squared end of the shaft 63 and the cam is secured outside the handle at the extreme end of the shaft.

The operation is as follows: the press 15 chamber being empty, the front and rear doors 6, 6^a, are closed, by seating the loops 91 of links 9 upon the cams, 10. The handle 20 is then thrown down from the position of Figure 4 to that of Figure 3, thus turning 20 the cams 10 and locking the doors. The press chamber is now filled with cotton and the follower actuated upward, to compress the cotton, within the upper baling chamber 8, against the platen 5. The bale being 25 formed, the handle 20 is shifted 180 degrees from the position of Figure 3 to that of Figure 4, in this operation the cam 10 being gradually turned from locking to release 30 position the doors gradually opening as the baled cotton expands as the restraint of the link members is released bringing the mutilated side 13 of the cam to the outside position, and permitting the loop 91 to slide off the cam, and the doors to open at the upper 35 side, as shown in Figure 4. The operation is a gradual release, as slow as desired, and without noise or jar, the operator standing to one side of the press in the operation of the handle 20. The doors may now be fully 40 opened and the bale tied and removed and the operation repeated.

I have described the essentials of my device, in its preferred form. In its preferred form the operating handle 20, is formed integrally with the hub of one of the cams. In 45 Figure 1 I show an alternative, in which the handle, 22, is separately formed and provided with a square aperture which may be seated upon the square end of the shaft, inside the cam, so that when the cam is released the handle will stand vertically above the shaft and when the cam is locked the handle 50 will depend, below the shaft. This alterna-

tive construction has the advantage that but one species of cam and hub is necessary and 55 cams are interchangeable at either end and the handle also may be mounted at either end of the shaft.

I claim:

1. In a cotton press, a securing and releasing mechanism for the press box door, comprising a pair of links, each secured at one end to one side of the press box, and having at the free end an engaging loop, the links crossing the ends of the press box; a shaft 60 mounted upon the free end of a press box door; mutilated eccentric cams upon each end of the shaft to receive the loops of the links; means to rotate the shaft and its cams, 65 to draw on or release the links, substantially 70 as described.

2. In a cotton press, a securing and releasing mechanism for the press box door, comprising a pair of links, each secured at one end to one door of a press box and having at the free end of the links an engaging loop, the links crossing the ends of the press box; a shaft 75 mounted upon the free end of the other door of the press box; mutilated eccentric cams at each end of the shaft, to receive the loops of the link; means to rotate the shaft and its cams, to draw on and release the links.

3. In a cotton press, a securing and releasing mechanism for the press box door, comprising a pair of links, each secured at one end to one side of the press box, each having at the free end an engaging loop, the links crossing the ends of the press box; a shaft 80 mounted upon the free end of a press box door on the opposite side of the press box; eccentric cams upon the ends of the shaft to receive the loops of the links, said cams being bevelled off upon the short radius of the 85 cam to remove the face of the cam to release 90 the loops, means to rotate the shaft and cams, to lock and release the door.

4. In a securing and releasing mechanism for a cotton press box door, an eccentric cam, having an operating face upon the long radius of the cam, and having the face bevelled off upon the short radius of the cam, substantially as described.

Signed at Dallas, Texas, this 16th day of April 1925.

WILLIAM L. HANCOCK.
